UNITED STATES PATENT OFFICE.

NATHANIEL E. DERRITT, OF HENNESSEY, OKLAHOMA.

SUPPORTER.

1,286,444.

Specification of Letters Patent. Patented Feb. 12, 1913.

Application filed May 21, 1912. Serial No. 160,930.

To all whom it may concern:

Be it known that I, NATHANIEL E. DERRITT, a citizen of the United States, residing at Hennessey, in the county of Kingfisher and State of Oklahoma, have invented new and useful improvements in Supporters, of which the following is a specification.

This invention comprehends the provision of a new article of manufacture in the nature of a combination sock and garter, the invention residing in the construction and arrangement of parts as claimed.

The figure in the drawing shows a perspective view of the article.

Referring more particularly to the drawing in detail 10 indicates a sock constructed from any suitable material, in the usual manner, and having secured to its upper edge, by stitching or otherwise, a triangular-shaped piece of material 11, which may be elastic or inelastic as desired. The material 11 is secured to the sock in the manner to present two of its corners uppermost, and projecting from one of these corners is an inelastic tape 12, while projecting from the opposite corner of the piece 11 is a relatively long elastic tape 13. It might here be stated that the component parts of the article may be constructed from any suitable material, and the tapes 12 and 13 vary in dimensions without departing from the spirit of the invention. It is of course obvious that the tape 13 is adapted to encircle

the limb of the wearer, and has its free end adjustably connected with the tape 12 with a view to varying the size of the garter. The tape 13 can be adjustably secured to the strip 12 in any suitable manner, but I preferably provide the strip 12 with a longitudinal series of eyelets 14, and the free end of the tape with a hook 15 for interchangeable engagement with the eyelets 14. A sock can be manufactured with a garter of the construction above described at a very small cost, and a possible separation of the garter from the sock, as well as its loss obviated.

What is claimed is:

A garment supporter comprising a triangular shaped piece of material to be attached to a sock, the said material disposed with two of its corners uppermost, a limb encircling tape secured at a point in its length to the projecting extremity of the triangular shaped piece of material across the entire width thereof, said tape having its extremities projecting beyond the opposite diverging sides of said material, one of said ends having a plurality of longitudinally extending eyelets, and a hook-like element carried by the opposite end of said tape for engagement with any one of said openings for securing the tape about the limb of the user.

In testimony whereof I affix my signature.

NATHANIEL E. DERRITT.
